[57] ABSTRACT

An extensible roll tree for use in apparatus in which continuous sheet material is continually cycled through an operational point from a storage area in which variable lengths of the sheet material are accumulated. The roll tree has two sets of rotatably mounted rolls about which the sheet material is entrained in a manner creating a plurality of stretches of the sheet material between the two sets of rolls. One of the sets of rolls is supported on a movable carriage which is reciprocally movable toward and away from the other set of rolls. A drive motor and a belt are connected to the movable carriage for moving it toward and away from the other set of rolls. This roll tree permits the plurality of stretches of the sheet material between the two sets of rolls to be increased or decreased as desired to accommodate greater or lesser lengths of sheet material in the accumulation area.

EXTENSIBLE ROLL TREE FOR FESTOONED SHEET MATERIAL

BACKGROUND OF THE INVENTION

1. Field of the Invention

This invention relates to apparatus for handling continuous sheet material such as films, tapes and webs, and more particularly, to an extensible roll tree for festooned continuous sheet material which has application, for example, in film projection apparatus and in film duplication apparatus.

2. Description of the Prior Art

There are many different situations where endless loops of film, tape, or other sheet material of different lengths is recycled through an operational station of one sort or another from a storage area. For example, this is particularly true in film duplication apparatus where one film having information on it is to be duplicated many times to form additional films containing the same information. In the past, this requirement has been met to a degree by merely transferring the master film from one reel to another through the operational station after which the reels were substituted and the process repeated. This obviously has been a rather slow process involving much waste of time and effort in changing reels and in rethreading the film.

In other instances, the master film has been formed into an endless loop as by joining its free end. This arrangement permitted the endless loop to be continuously recycled through the operational station such as the exposure station in which duplication occurred. One of the problems associated with this arrangement has been the difficulty of carefully handling the residual portion of the loop being recycled so that damage to the imaged information on the film was avoided and yet so that the film would flow freely and reliably through the storage chamber without tearing or breaking. Another difficulty experienced has been the problem of accommodating different lengths of accumulated portions of the film loop within a given space since such films often vary considerably in total length. This latter problem is most frequently experienced with microfilm storage records in which the length is totally governed by the allotted information to be recorded and stored.

In view of the above difficulties and shortcomings of the prior art apparatus for handling continuous sheet material of this nature, a new and improved form of apparatus was discovered which was capable of accommodating endless film loops differing vastly in their length. This apparatus is particularly reliable in smoothly recycling such an endless film loop through an operational station in a manner which minimizes degradation of the master film loop and the imaged information thereon.

Thus, the principal object and advantage of the present invention is to facilitate the storage and recycling of an endless master film loop through an operational station.

A further object and advantage of the present invention is to facilitate the application of a continuous film loop onto a roll tree.

SUMMARY OF THE INVENTION

The present invention is apparatus for handling continuous sheet or strand material such as films, tapes, webs and threads and includes an extensible roll tree

for festooned continuous sheet or strand material. The roll tree includes first and second sets of rotatably mounted rolls upon which said sheet material is entrained in a manner creating a plurality of stretches of the sheet material between the first and second sets of rolls. A movable carriage means supports the first set of rolls and is reciprocally movable toward or away from the second set of rolls. Actuating means are operably connected to the movable carriage means to move it alternatively toward or away from the second set of rolls. In this manner, the length of the plurality of stretches of the sheet material between the first and second sets of rolls is alternatively increased or decreased. This facilitates the application of the film loop to the roll tree since the roll tree can be extended after application of the film loop in order to take up any slack.

The actuating means include a continuous drive belt secured to the carriage means and an electric motor operably connected to the drive belt in a reversible mode. The rolls in each of the first and second sets have parallel rotational axes and are sufficiently spaced apart from one another to eliminate contact between the stretches of sheet material between the first and second sets of rolls. The carriage means include a movable upright support on which the first set of rolls is rotatably mounted and guide means are provided to direct the movement of the upright support toward and away from the second set of rolls. In one embodiment, the guide means include an elongate stationary guide element which extends along the path of desired movement of the upright support, and a movable slide element fixed to the upright support and slidably attached to the guide element for cooperative movement along at least a portion of its length. In a particular embodiment, the extensible roll tree of the invention is employed in film projection or duplication apparatus for handling an endless film loop.

DESCRIPTION OF THE DRAWINGS

Additional objects and advantages of the present invention will become apparent from the following description thereof taken in conjunction with the drawings, wherein:

FIG. 1 is a side elevation view of one form of microfilm duplication apparatus through which an endless loop of microfilm is fed, and

FIG. 2 is a sectional side elevation view of an extensible roll tree of the invention which is used to cycle the loop of microfilm through the apparatus shown in FIG. 1.

DETAILED DESCRIPTION OF THE PREFERRED EMBODIMENT

FIG. 1 shows a portion of one form of film duplicating apparatus in which the present invention is utilized. The film duplicating apparatus includes a rotatably mounted support cylinder 10 on the surface of which an unimaged photosensitive duplicating film 11 is supported. An original master film 12, that is, a light-stable, previously exposed film which already contains a developed visible image, is superimposed upon the duplicating film 11. The films 11 and 12 are supported in this manner and run in contact with one another and the surface of the support cylinder 10 through about 270° of rotation of the support cylinder 10. The

duplicating film 11 is fed onto the support cylinder 10 from a feed reel 13 and after it passes around a guide roller 14, a guide roll 15, and a guide roller 16. Upon leaving the support cylinder 10, the duplicating film 11 passes around a guide roller 17 and advances through an opening 18 in the dividing wall 20 and into the developing chamber 21 where it is developed in accordance with well-known techniques, the nature of which depends upon the type of film system employed.

The duplicating film 11 is of a nature such that it is photosensitive, so that when it is exposed to a light-shadow image, as by transmission of light through the master film onto the duplicating film, a developable image will be created on the duplicating film. The duplicating film 11, for example, may be of a conventional silver halide form or of a conventional diazo form, the nature of each being well-known to those skilled in photography and copying.

FIG. 1 shows the type of developing chamber commonly employed for developing a diazotype film, in which the film is exposed to ammonia gas formed by volatilizing an aqueous ammonia solution by heating means (not shown) to develop the image thereon. To insure exposure of the film to ammonia for a sufficient time while it is continuously fed into the chamber 21, a substantial length of the film is accumulated within the chamber 21 by running it between a plurality of rollers 22 to create many stretches of the film which permit exposure of the film surface to the atmosphere in chamber 21. The developed film is fed through a second opening 23 in dividing wall 20 and is passed over guide roll 24, guide roll 25, and guide roll 26, after which it is wound upon a reel 27.

The master film 12 is fed from the extensible roll tree of the invention, described subsequently with reference to FIG. 2, around a snubbing roller 28, and then around a guide roller 30, after which it is fed around the periphery of the support cylinder 10 on top of the duplicating film 11. Upon leaving the support cylinder 10 and the duplicating film 11, the master film 12 is fed around a guide roller 31 and then around a snubbing roller 32, around guide rollers 33, 34 and 35, after which it is fed back to the extensible roll tree of the invention. The entire film system is driven by a drive motor (not shown) operably connected by a belt (not shown) to pulleys (not shown) on certain of the guide rollers and reels as are necessary to advance the duplicating film 11 and the master film 12 through the apparatus. Therefore, it is frictional force between the films 11 and 12 and the outer periphery of the driven rollers which advances the duplicating film 11 and the master film 12 around the support cylinder 10 and through the duplicating apparatus. These details have been omitted to avoid obscuring the invention, but the details of such a drive arrangement would be readily apparent to one skilled in the art.

The side wall 36 of the duplicating apparatus has an opening 37 therein radially disposed from the support cylinder 10. A light chamber 38 is formed by spaced-apart upper and lower inclined walls 40 and 41, respectively, radially extending from the side wall 36 at the top and bottom of the opening 37 to a point closely spaced from the surface of the support cylinder 10 and side walls 42, only one of which is shown, which connect the respective ends of upper and lower walls 40

and 41 to generally define an exposure station, indicated generally by the bracket 43. Thus, exposure of the duplicating film 11 to light projected through the master film 12 only occurs when the films 11 and 12 pass over the support cylinder 10 between the lower side wall 41 and the upper side wall 40.

A lamp 44 is spaced from the side wall 36 in line with the opening 37 therein. The lamp 44 is partially enclosed by an arcuate reflecting element 45 and outwardly diverging upper and lower reflecting elements 46 and 47, respectively, spaced apart from one another. All of the reflecting elements 45, 46 and 47 combine to project light from the lamp 44 through the opening 37 into the light chamber 38 and through the master film 12 onto the duplicating film 11 as they move through the exposure station 43. The lamp 44 may comprise any of the high intensity electric light sources typically employed in projection apparatus and film duplicating equipment.

A shutter 50 is disposed adjacent the side wall 36 and the opening 37 therein, and is movable from an open position where it is adjacent the side wall 36 as shown in FIG. 1 in solid line, to a closed position where it is in front of the opening 37 and is in front of the space between the reflecting elements 46 and 47, as shown in phantom line in FIG. 1. In the open position, light from the lamp 44 can strike the films 11 and 12 at the exposure station 43, but in the closed position, light which enters the light chamber 38 is essentially precluded from striking the films 11 and 12 at the exposure station 43. Movement of the shutter 50 is accomplished by a rack and pinion mechanism, the shutter 50 being attached to the lower end of the rack 51 which is meshed with and driven by a pinion gear 52 which is attached to the drive shaft of a shutter drive motor 53. The shutter drive motor 53 is a reversible AC motor and the direction of its operation may be controlled by a simple switch (not shown) or by more automatic means (not shown), the arrangement and operation of which would be understood by those skilled in the art.

A pressure roller 54 is disposed within the light chamber 38 and arranged to contact the surface of the master film 12 to press it against the duplicating film 11 just prior to the point where the films 11 and 12 are struck by light. This pressure substantially eliminates any air gaps between the two films 11 and 12 and ensures uniform contact therebetween which is essential to avoid undercutting of the image during exposure. In the duplication of images, and particularly micro-images on microfilm, close contact during exposure to light is extremely important to avoid the loss of resolution which otherwise occurs due to non-radial or diverging light rays passing through the imaged film. Such diverging light rays tends to undercut the image on the master film 12 if the master film 12 and the duplicating film 11 are not in close contact with one another. This results in a dim or light image with reduced resolution.

The pressure roller 54 is rotatably mounted on one end of a pivotably mounted support arm 55 which pivots about a pin 56 connected to the side plate 42. The other end of the support arm 55 is connected by a tension spring 57 to the back side of the lower reflecting element 47. From this arrangement, it can be seen that the pressure roller 54 is spring-biased into contact

with the master film 12 when the shutter 50 is open. In accordance with the invention, the pressure roller 54 is moved away from and out of contact with the master film 12 when the shutter 50 is moved to its closed position. This is accomplished by the lower end of the shutter 50 striking the support arm 55 holding the pressure roller 54 and overcoming the force of the spring 57 by the force of the shutter drive motor 53 operating through the rack 51 and pinion gear 52 so that the pressure roller 54 is pivoted out of contact with the master film 12. This position of the support arm 55 and pressure roller 54 is shown in phantom in FIG. 1.

Referring now to FIG. 2 of the drawings, one form of an extensible roll tree of the invention is shown which is embodied in a unit to be disposed directly beneath the apparatus shown in FIG. 1 and described above. The unit is designed to accommodate endless film loops of varying lengths such as loops of microfilm of which copies or duplicates are to be made. The extensible roll tree is designed to maintain the accumulated length of the master film loop 12 in condition for continuous recycling through the duplication portion of the apparatus shown in FIG. 1, and to receive the master film 12 after it has been duplicated.

The extensible roll tree has a base 60 and an upstanding stationary support member 61 near one end thereof containing a plurality of rotatably mounted rolls 62 depending outwardly therefrom and arranged along a line in spaced-apart relation to one another. Another upstanding support member 63 is spaced from the stationary support member 61 and also carries a plurality of spaced-apart, rotatably mounted rolls 64 depending outwardly therefrom and having their rotational axes generally parallel with the rotational axes of the rolls 62 on the support member. Master film 12, received from the duplicating portion of the apparatus shown in FIG. 1, is fed downwardly along one end of the apparatus shown in FIG. 2 and about a guide roller 65 and hence alternately to successive rolls 62 and 64 on the upstanding support members 61 and 63, respectively, so as to form a plurality of stretches of the master film 12 extending between the support members 61 and 63. The master film 12 is then fed about guide rolls 58 and 59 and back into the duplication unit. In this manner, a considerable length of the master film 12 can be accumulated and stored while another portion thereof is continuously fed through the duplication portion of the apparatus.

The support member 63 is reciprocally movable toward and away from the support member 61 containing the set of rolls 62 so that it serves as a movable carriage for the set of rolls 64. Guide means are provided for controlling the path of movement of the support member 63 and the rolls 64 carried thereon. The guide means in the embodiment shown in FIG. 2 comprise an elongate stationary guide member or bar 66 extending from one end of the apparatus to the other, the respective ends of the bar 66 being carried in sockets in the spaced end plates 67 and 68. A movable slide member 70 is fixed to the movable upright support member and partially encircles the guide member 66 so that it is slidably attached thereto for cooperative movement along its length. It will be apparent that when the upright support member 63 is moved away from the stationary support member 61, the lengths of sheet

material such as the master film 12 between the respective rolls 62 and 64 on the support members 61 and 63 become greater, thereby permitting a longer film loop to be accumulated and fed through the duplicating portion of the apparatus. On the other hand, where a shorter length of film is to be duplicated, the support member 63 may be moved toward the support member 61 and, in certain instances, fewer of the rolls 62 and 64 on each of the respective support members may be employed to accumulate the shorter film loop. Movement of the rolls 62 and 64 together also facilitates the insertion of the film loop onto the roll tree of the invention, since the slack can then be taken up after only a short length has been threaded over the rolls 62 and 64 by moving the rolls 62 and 64 apart again.

In the embodiment shown in FIG. 2, actuating means are shown for moving the movable carriage or upstanding support member 63 toward and away from the stationary support member 61. These actuating means include an endless drive belt 71 which is fixedly secured to the slide member 70. The drive belt 71 passes around idler pulleys 72 and 73 rotatably mounted on the back wall 74 of the apparatus at each end thereof. The belt 71 also passes around a drive roller 75 through which it is driven and a snub or tension roller 76. The drive roller 75 is fixed to a drive pulley 77 which is driven by a drive belt 78 by means of a pulley 80 fixed to a drive motor 81. The drive motor 81 is a reversible AC type of motor which is electrically connected to a source of electrical power 82 through a variable transformer 83. In operation, the drive motor 81 operating through the drive pulley 77, drive belt 78, and drive pulley 80, turns the drive roll 75 and moves the belt 71 in one direction or the other, as desired and as controlled by switching means (not shown) of a type well-known to those skilled in the art, so that the upright support member 63 is pulled along its path toward or away from the upright support member 61. Movement toward member 61 permits an endless loop of microfilm, which is to be duplicated, to be easily inserted into the extensible roll tree. Movement of member 63 away from member 61 eliminates any slack in the endless loop, and the stretches of film material between the respective support members 61 and 63 are tautened, spaced apart and made generally parallel to eliminate moving contact between stretches of the film which might result in damage to the image thereon or to the optical clarity of the film.

In view of the above description of the invention and of the drawings, it will be apparent that a new and improved extensible roll tree is provided for festooned continuous sheet material such as an endless film to be duplicated. It is also apparent that the extensible roll tree of the invention enables endless film loops to be accumulated and recycled through apparatus such as film duplication equipment and to accommodate film loops of differing lengths. Furthermore, it can be seen that the roll tree of the invention greatly facilitates the repetitive duplication on microfilm strips where numerous copies are to be made, while overcoming many of the problems previously experienced with apparatus of this general type.

From the above description of the invention, it will be apparent that various modifications may be made in the specific embodiments disclosed in detail herein,

without departing from the spirit and scope of the invention. For example, the precise manner in which the lengths of film are arranged within the apparatus is not in any way critical to the invention. Furthermore, many different forms of actuating means for moving one of the set of rolls relative to the other may be employed with equal success. It should be clearly understood that the terms "sheet material, films, tapes, webs, strands or threads" are used interchangeably except where a particular function is ascribed to one type, and the scope of the invention is not to be restricted by such terms as any of such materials can be advantageously handled by the roll tree of the present invention. Therefore, the invention is not intended to be limited in any way to the specific forms or applications described herein except as may be required by the following claims.

What is claimed is:

1. In apparatus for duplicating film, wherein an original master film containing imaged indicia and a duplicate film are brought into overlying relationship with one another and light is projected through said master film and onto said duplicate film at an exposure station, and said apparatus includes film drive means for advancing said films through said exposure station, a light source for directing light toward said films at said exposure station, means for feeding said duplicate film into the apparatus for exposure and means for receiving the duplicate film after exposure and for developing said image,

the improvement comprising an extensible roll tree for a festooned endless master film loop adapted for continually feeding said master film to said exposure station and receiving said master film from said exposure station, whereby a series of copies of said master film loop is automatically made on said duplicate film, said extensible roll tree comprising: first and second sets of rotatably mounted rolls about which said master film loop is entrained in a manner creating a plurality of stretches of said master film between said first and second sets of rolls;

movable carriage means for supporting said first set of rolls, said movable carriage means being reciprocally movable toward and away from said second set of rolls; and

actuating means comprising a continuous drive belt operatively connected to said movable carriage means and an electric motor operatively connected to said drive belt in a reversible mode for moving said movable carriage means alternatively toward and away from said second set of rolls, whereby the length of said plurality of stretches of said master film between said first and second set of rolls is alternatively increased or decreased.

2. The improvement in apparatus for duplicating film according to claim 1, wherein the rolls in each of said first and second sets have parallel axes of rotation and are sufficiently spaced apart from one another to eliminate contact between said stretches of said master film between said first and second set of rolls.

3. The improvement in apparatus for duplicating film

according to claim 1, wherein said carriage means comprise a moveable upright support on which said first set of rolls is rotatably mounted, and said roll tree includes guide means for directing the movement of said upright support toward and away from said second set of rolls.

4. The improvement in apparatus for duplicating film according to claim 3, wherein said guide means include an elongate stationary guide element which extends along the path of desired movement of said upright support, and a moveable slide element fixed to said upright support and slidably attached to said guide element for cooperative movement along at least a portion of its length.

5. In apparatus for duplicating film, wherein an original master film containing imaged indicia and a duplicate film are brought into overlying relationship with one another and light is projected through said master film and onto said duplicate film at an exposure station, and said apparatus includes film drive means for advancing said films through said exposure station, a light source for directing light toward said film at said exposure station, means for feeding said duplicate film into the apparatus for exposure and means for receiving the duplicate film after exposure and for developing said image,

the improvement comprising an extensible roll tree for festooned endless master film loop adapted for continually feeding said master film to said exposure station and receiving said master film from said exposure station, whereby a series of copies of said master film loop is automatically made on said duplicate film, said extensible roll tree comprising: first and second sets of rotatably mounted rolls about which said master film loop is entrained in a manner creating a plurality of stretches of said master film between said first and second sets of rolls;

movable carriage means for supporting said first set of rolls, said movable carriage means being reciprocally movable toward and away from said second set of rolls, said carriage means comprising a movable upright support on which said first set of rolls is rotatably mounted;

guide means for directing the movement of said upright support toward and away from said second set of rolls; and

actuating means operatively connected to said movable carriage means for moving it alternatively toward and away from said second set of rolls, whereby the length of said plurality of stretches of said master film between said first and second set of rolls is alternatively increased or decreased.

6. The improvement in apparatus for duplicating film according to claim 2, wherein said guide means include an elongate stationary guide element which extends along the path of desired movement of said upright support, and a moveable slide element fixed to said upright support and slideably attached to said guide element for cooperative movement along at least a portion of its length.
